UNITED STATES PATENT OFFICE.

LOUIS HÉÉ, OF SOUTH RIVER, NEW JERSEY.

PADLOCK.

1,168,884.

Specification of Letters Patent. Patented Jan. 18, 1916.

Application filed May 25, 1915. Serial No. 30,322.

To all whom it may concern:

Be it known that I, LOUIS HÉÉ, a subject of the King of Hungary, residing at South River, in the county of Middlesex and State of New Jersey, have invented new and useful Improvements in Padlocks, of which the following is a specification.

This invention relates to improvements in padlocks, and particularly to a keyless type of the permutative variety.

One object is to provide a lock of the type described which cannot be picked or opened unless the operator is familiar with the combination.

Another object is to provide a lock which is strong, light and cheap to construct.

These objects are attained by the novel construction and combination of parts hereinafter described and shown in the accompanying drawing, forming a material part of this specification and in which:

Figure 1 is a side elevation of a padlock made in accordance with the invention, shown in a closed position, the broken lines indicating the position of parts when partially unlocked. Fig. 2 is an edge view of the same. Fig. 3 is a side view of the lock, the cover plate being removed showing the interior and the bow indicated in an open position by the broken lines, Fig. 4 is a vertical sectional view, taken on line 4-4 of Fig. 3, and Fig. 5 is a view indicating the operation of the releasing block.

The main body 10, is preferably shield shaped in outline, with flanged integral edges 11 except for openings at the top for the ends of the bow 12, secured by the pivot 13, which also passes through the cover 14, further held in place by rivets 15 at various points as indicated.

One end of the bow 12, has an extension 16, reaching into the lock beyond the pivot 13, and bearing against it is a flat spring 17 rigidly secured to the inner side of the flange in such manner as to exert a constant pressure tending to open the lock. The other end of the bow is formed with a hook 18 adapted to enter a narrow opening in the top of the flange and engage with a detent 19, pivoted at 20 and pressed inwardly, toward the center of the lock, by the spring 21, which is also fastened to the inner side of the flange and tends to keep the detent engaged with the bow hook, positively locking the bow, as can be seen in Fig. 3.

The detent 19 is held in locking engage-

ment by means of the tumbler 22, shown in Fig. 3 in an unlocked position, but which can be so revolved as to prevent the detent from turning on its pivot 20. The tumbler 60 can be turned by the stem 24 attached to dial 23, which is rotatably mounted on the cover 14, by means of its corrugated edges, the dial being provided with lined characters which can be brought into registration with a mark 65 on the surface of the cover.

A further locking means, preventing the detent 19 from turning on its pivot, is provided by the T or L shaped stop 25 extending through the side flange and having 70 an operating block 26 rigidly engaged with it in such manner that when the block edges of the stands parallel with the sides of the lock body the stop 25 will register with, and enter into a depression 36, formed in 75 the edge of the detent 19, as the detent is moved in a direction to unlock the bow; but when the block is in its normal position, that is transverse to the edge of the lock, the stop will not enter the depression but by 80 reason of its angularly turned portions acts to prevent the detent from moving. A similar block 27 is pivoted on the opposite edge of the lock and both blocks are provided with lugs 28 and 29 respectively which engage normally with corresponding depressions in the end of the swinging bar 30, which is pivoted at its center 31 on the face or cover of the lock plate 14.

The function of the bar 30 is to hold the 90 blocks 26 and 27 in their proper transverse position and also to impart an initial turning effect to them when the bar is rotated, as indicated in Fig. 1. When the blocks are 95 so turned, parallel with the sides of the lock, and the tumbler rotated by the dial into its open position, the lock can be opened by exerting pressure upon the pin 32, the enlarged inner end 33 of which abuts against the lower end of the detent 19, causing the 100 latter to turn on the pivot 20 and disengage the hook 18, whereupon the bow 12 opens under the pressure of the spring 17, the projection 16 contacting with the fixed stop 34, which also prevents the bow from entering the lock to an excessive depth. Thus 105 there is provided a padlock having three distinct means for holding the bow in an engaged position, each means requiring separate and distinct manipulation to accomplish unlocking.

Having thus described the invention, its

construction, functions and use, what I claim as new and desire to secure by Letters Patent is:—

1. In a padlock, the combination with a body, a bow pivoted therein and an open hook formed with said bow, of a detent engageable with said hook, said detent having a longitudinal recess formed in its outer edge, means for disengaging said detent, 5 a rotatable stop normally preventing said disengaging means from operating and means for registering said stop with the mentioned recess whereby said disengaging means may be operated.

2. In a padlock, the combination with a casing, of a shackle-bow pivoted therein, said bow having a part whereby its motion is limited, an open hook formed with said bow, a pivoted detent engageable with said hook, plates pivoted on the sides of said casing, a stop combined with one of said plates operatively engageable with said detent, a bar pivoted on the face of said casing for actuating said plates and means for actuating said detent when released from engagement by said stop. 15 20 25

LOUIS HÉÉ.
